PENCIL

Frank C. Deli, Chicago, Ill., assignor to Auto-point Company, Chicago, Ill., a corporation of Illinois

Application December 7, 1934, Serial No. 756,420

9 Claims. (Cl. 120—18)

My invention relates to pencils, and particularly to pencils of the type known in the trade as "propel and repeal". In this type the lead may be advanced and retracted by relative right hand and left hand rotation of the propelling mechanism.

The object of my invention is to provide a pencil of the character described that may be economically constructed, easily assembled, and that will operate correctly for long periods without disarrangement. Specific objects and advantages will be discussed in the accompanying description.

The invention will be more readily understood by reference to the accompanying drawing, in which:

Fig. 1 is a longitudinal, sectional view through a pencil constructed in accordance with my invention;

Fig. 2 is an enlarged longitudinal, sectional view of the lower end construction, showing the parts in lead-ejecting position;

Figs. 3, 4, and 5 are enlarged sectional views on the lines 3—3, 4—4, and 5—5 respectively of Fig. 1;

Fig. 6 is a plan view of the lead shuttle and ejector in assembled relation;

Fig. 7 is a longitudinal sectional view through a pencil barrel of slightly different form;

Fig. 8 is a sectional view on the line 8—8 of Fig. 7; and

Fig. 9 is a sectional view through a completed pencil having a barrel such as is shown in Fig. 7, and containing the operating mechanism shown in Figs. 1 to 6 inclusive.

In the drawing, and referring to the mechanism shown in Figs. 1 to 6, I have illustrated a pencil body or barrel 10, having an axial opening, and partly lined with a lead magazine member 11.

This member is of incomplete tubular form as best shown in Fig. 5, the marginal edges 12 being bent inward to occupy radial position and serving to define a lead chamber 13, for the reception of long leads 14. At a point near the rear end of the member 11, I deflect the metal inwardly, as at 15, the projection so formed, together with the radial flanges 12 defining a space that is eccentric to the axis of the barrel, and of a diameter corresponding substantially to that of the spiral 16, later to be described. As a result of this arrangement of parts, the spiral is deflected sufficiently from one side of the barrel to provide a space to accommodate spare leads.

An eraser ferrule 17 is projected into the open upper end of the barrel, the ferrule being shaped

to receive an eraser 18 and its associated bushing 19, the parts being surmounted by a cap 20.

The operating mechanism includes a tip, consisting of a metal part 21 having a shank 22, and a molded part 23, preferably composed of bakelite, that is molded in place over the shank 22. Mounted within the shank 22 is a lead tube 24, substantially all of the part within the shank 22 being of complete cylindrical form, while the part 25 extending to substantially the upper end of the barrel has an open slot 26 therein, as shown in Figs. 3, 4, and 5.

The lead tube is anchored within the shank of the metal tip as best shown in Figs. 2 and 3 by deflecting or upsetting a portion 27 of the shank 15 into the slot 26 in its extreme lower end. Thus the lead tube is held against rotation and longitudinal movement relative to the tip.

The open spiral 16 is fixed to the barrel by means of a sleeve 28, the lower end of which is slotted, the sleeve being joined to the spiral by means of a projection or lug 29 on the spiral that interfits with a corresponding recess in the metal of the sleeve at its upper end. The sleeve has a very tight friction fit in the axial opening in the lower end of the barrel. The portion of the sleeve 28 that projects beyond the lower end of the barrel is slotted, as stated, and the walls are thinned somewhat, as indicated at 30, to permit the slotted end to project into a space provided in the upper end of the bakelite tip 23. The relief, or thinning, permits the sleeve to be slightly compressed, and thus insures a continued frictional resistance to relative rotation between the tip and body without conflict with the spiral. Of course, the same result may be secured by slightly flaring the projecting, slotted portion of the sleeve and providing a slightly enlarged opening in the tip to compensate therefor.

The lead clutch, or shuttle, 31 is formed from a section of thin spring bronze, is of tubular form, having a continuous slit from end to end thereof, and at a point intermediate its ends, the twin lugs 32, 33 are formed. These lugs are shaped from the opposite edges of the metal, and when formed are spaced apart, as at 34. The edges 35 are arranged diagonally to correspond to the taper of the spiral. The arrangement is such that, in order to insert the twin lug within the convolutions of the spiral, it is necessary to compress the two parts against the spring of the metal. The movement of the two parts of the lug, as the result of such compression, being angular to the longitudinal axis of the spiral, the fit between the lug and the spiral will always be 55

resilient and tight. Thus, there will be no play or lost motion in reversing the motion of the lead.

The shuttle slides freely within the lead tube and, at its upper end, is slotted, as at 36, to receive the projecting lug 37 of the follower, or ejector, 38. An extension 39 of the follower projects beyond the lug 37, and is adapted to underlie the spiral and to prevent jamming at the extremity of movement of the ejector.

10 It will be understood that these parts are small and fragile, particularly the ejector and that when an excessive force is applied as may occur at the limit of movement, the tendency is to force the lug up into the spiral and to bend the ejector.

15 As heretofore described, the spiral is caused to occupy a position eccentric to the axis of the pencil, this being permitted by reason of the resiliency of all the parts, and of slight clearance, or play, sufficient to allow the necessary lateral deflection. At the upper end a fiber washer 40, and a metal ring 41 surround the lead tube, the washer abutting the end of the spiral to provide a thrust member. The ring and washer are anchored by spreading, or flaring, the free end of 20 the lead tube, as indicated at 42.

In the construction shown in Figs. 7, 8, and 9 the operating mechanism is identical. However, in the use of a molded bakelite barrel 43, a chamber 44 can be provided therein. It is, however, 30 necessary to deflect somewhat the free end of the spiral and to accomplish the purpose I form lugs 45 on the eraser ferrule 46. In this case I find it unnecessary to deflect the spiral throughout the full length of the chamber.

35 The operation is as follows. With the ejector retracted, which will occur following the first reverse movement of the parts, a lead, such as indicated at 14, in Fig. 1, is projected into the open lower end where it is frictionally engaged by the 40 lower end of the shuttle 31. Further backward movement will draw the lead rearwardly into the position shown in Fig. 1. Thereafter, the lead is fed forward, as required, until the twin lug 32-33 runs out of the spiral and is stopped, as 45 shown in Fig. 2. Continued forward rotation will cause the ejector to travel forward in the slot 36 of the shuttle and eject the lead, as shown in Fig. 2.

Obviously, the construction is capable of modification, and I do not wish to be limited except as indicated in the appended claims.

I claim:

1. In a pencil of the "propel-repel" type, the combination of a barrel, and a relatively rotatable 55 tip, a spiral fixed relative to the barrel, lead advancing mechanism operated by the tip and co-operating with said spiral, means in the barrel for deflecting the spiral away from the axis of the barrel to provide a reserve lead chamber 60 alongside of said spiral, said means providing side walls for defining the lateral limits of said lead chamber.

2. In combination, a barrel having an axial chamber, a spiral fixed in said chamber and of 65 substantially less diameter than said chamber, lead advancing mechanism co-operating with said spiral, and means for permanently deflecting said spiral out of axial alignment in said chamber to provide a reserve lead chamber in the 70 space alongside of said spiral, said means providing side walls for defining the lateral limits of said lead chamber.

3. In combination, a barrel having an axial chamber, a spiral fixed in said chamber, a tip 75 and lead advancing mechanism carried thereby

and co-operating with said spiral, a tubular member within said chamber having a slot, the marginal edges of which are bent inward to a radial position, said bent edges constituting flanges that serve to deflect said spiral out of axial alignment and to define the sides of a reserve lead chamber.

4. In combination, a barrel having an axial chamber, a spiral anchored to the barrel at the lower end thereof, a split sleeve projecting from 10 the opening in the lower end of the barrel, a tip mounted for rotation on said split sleeve, a lead tube fixed to the tip and projecting through the spiral and fixed for rotation to the upper end of the spiral, and lead advancing mechanism pro- 15 vided in the tube.

5. In combination, a tubular barrel, an open spiral fixed in the lower end of the barrel, a resilient tubular projection over-lying the spiral and projecting beyond the lower end of the barrel, a tip mounted on the projection with capacity 20 for rotation, a lead tube anchored in the tip and projecting through the spiral and rotatively fixed beyond the upper end thereof, and lead advancing mechanism in said tube and operated by relative rotation of said tip and barrel.

6. In combination, a tubular barrel, a spiral fixed therein providing a track, a tip rotatively connected to said barrel, a slotted lead tube fixed to the tip and extending axially through said 30 spiral, a shuttle within said lead tube, said shuttle having a lug engaging the spiral and operating in the slot in said lead tube, said shuttle being in the form of a slit tube of resilient material, the slit in said tube extending through said lug, 35 the dimension of the lug transversely of the spiral track, being greater than the transverse dimension of the track, whereby the lug must be compressed in order to enter the space between the convolutions of the spiral.

7. In combination, a tubular barrel, a spiral fixed therein and providing a spiral track, a tip rotatively connected to said barrel, a slotted lead tube fixed to the tip and extending axially through said spiral, a shuttle within said lead tube, said shuttle having a lug engaging the spiral and operating in the slot in said lead tube, said shuttle being of tubular form and the lug thereon being slit in an angular line relative to the axis of the tube, said slit providing for compression of 45 the lug in order to enable it to occupy said spiral track.

8. In a pencil, the combination of a tubular barrel, a spiral anchored therein, a tip consisting of a metal terminal portion having a shank, and 55 a non-metal portion mounted on said shank, a lead tube anchored in said shank, the tube being of full cylindrical form in substantially all of the portion engaging the shank and slotted throughout the remainder of its length, a portion of the 60 metal of the end of shank being deflected into said slot to anchor the tube within the shank against relative longitudinal and angular motion, and lead advancing mechanism carried in said tube.

9. A shuttle for use in a pencil of the propel-repel type, said shuttle being in the form of a slit tube of resilient material and having a lug formed thereon, the slit in said tube extending diagonally across said lug, the dimension of the 65 lug between the faces that engage with a spiral track provided in said spiral track whereby the lug must be compressed in order to occupy said space.
